UNITED STATES PATENT OFFICE.

HENRY W. MORGAN, OF ROCHESTER, NEW YORK.

NAILING MACHINE.

Application filed March 2, 1923. Serial No. 622,375.

My present invention relates to machinery and more particularly to nailing machines and has for its object to improve the driving mechanism of these machines in such manner that it will be self adjusting when operating upon work pieces of different thicknesses whereas it has hitherto been necessary to make fixed adjustments of the nailing mechanism for each thickness of work or else raise the thinner pieces on the table of the machine. This invention is an improvement upon that shown in my prior co-pending application, Serial Number 601,433 filed November 16, 1922, and it has for a further object to provide an improved working relationship between the driver and the nail chuck by rendering the latter self adapting to the work piece. To these and other ends the invention resides in certain improvements and combinations of parts all as will be hereinafter more fully described, the novel features being pointed out in the claims at the end of the specification.

In the drawings:

Figure 1 is a front view partly broken away and with a fragment of the work piece in section showing the driving mechanism of a nailing machine constructed in accordance with and illustrating one embodiment of my invention.

Figure 2 is a vertical central section through the same in a plane extending from front to rear of the machine.

Figure 3 is a section taken in a relatively transverse plane to that of Figure 2 illustrating the action upon a work piece of greater thickness.

Figure 4 is a horizontal or transverse section taken on the line 4-4 of Figure 2.

Figure 5 is a section taken on the line 5-5 of Figure 2.

Figure 6 is a side view of the driving mechanism partly in section through the work piece and through an adjacent fragment of the machine and

Figure 7 is a view like Figure 6 but with the parts in another position.

Similar reference numerals throughout the several views indicate the same parts.

The improvements are shown embodied in a nailing machine of a familiar type in which 1 indicates the vertical side frame provided with ways 2 upon which reciprocate vertically the guides 3 of the cross head 4 constituting the driving head of the driving mechanism. The head is reciprocated

vertically by a pitman 5 connected to it by a wrist pin 6 and actuated by mechanism which does not concern the present invention.

Secured to the front of the frame beneath the driving head is a table 7 for the work which in the present embodiment and description we will assume to be boxes. Immediately above the table there is mounted on the frame 1 by means of adjustable brackets 8, cross bars 9 upon which the castings 10 containing the nail chucks are secured for lateral adjustment by bolts 11 in a novel manner hereinafter described.

Assuming that a box of the general nature shown at A is to be nailed, the chuck holding devices are adjusted so that the mouth of the chuck 13 will clear by the proper distance the top surface of the completed box and then the travel or stroke of the driving head 4 is adjusted by means not shown to carry the driver 14 on the driving stroke just far enough out of the mouth of the chuck to set the nail head the desired distance in the work piece. Heretofore it has been necessary to have the surface in which the nail is driven always in the same plane for a given adjustment of the nailing mechanism because the driver was positively driven on a set stroke and it would not drive the nails and set them uniformly in the work unless this condition obtained. Therefore, in constructing a box of the nature shown at A in Figures 6 and 7 it was necessary, in first nailing one of the tops B to the ends C, to place the other unnailed top D beneath the said end to bring the surface of B up high enough for the driver. The box was then turned over to the position of

said figures and the top D nailed in place with the surface thereof in the same plane previously occupied by that of the top D. This, however, necessitated holding the three loose pieces together in a sort of balanced relationship on the table while the preliminary nailing was being done which was difficult and inconvenient, the manipulation of the un-nailed top during the nailing of the other resulting in a considerable loss of time.

It is obviously much easier for the operator to merely place the end C edge wise on the table 7; nail one top piece to it at the height of its own thickness plus the height of the end piece; to turn these two over and then apply the other top and nail it at a greater height or at one to which its

own thickness has been added. With my present invention this can be done without readjustment of the driving head for the following reasons:

5 Instead of mounting the driver 14 in fixed relationship to the driving head 4, I provide the latter with a hollow, tubular guide casing 15 formed with lug 16 at its top by means of which it is retained in the head 10 by the usual transverse locking bar 17. Inside of this guide case is a block or head 18 to which the driver 14 is rigidly fixed and which comprises a cylindrical extension 19 having a further bearing for limited sliding 15 movement in the bottom of the case through which it projects. The upper end of the guide case 15 is closed by an adjustable threaded plug 20 having a cupped interior and interposed between this plug and the head 18 of the driver is a compression spring 21. It will thus be seen that the driver is capable of yielding and that the driving head presses the driver downwardly only through the medium of this 25 spring 21.

The chuck 10 is of the usual split yielding type with spring jaws 22 through which the nail is forced by the driver after being deposited in the feed channel 23 from the nail tube 24. It is mounted for limited vertical reciprocatory movement on the supporting bars 9 for which purpose it is fitted with an offset guide strap 24^a embraced by a yoke 25 (Figures 2 and 4) on a casting 30 35 40 45 50 55 that receives the bolt 11 previously referred to. Within this casting 26 is a spring socket or chamber 27 containing a spring 28 resting on a plug 29 at the bottom and reacting at its upper end where it projects from the casting against the shoulder 30 on the chuck recessed to receive it as shown. The tendency of this spring 28 will be seen to be to hold the chuck raised on the supporting bars, the yoke 25 engaging a shoulder 31 on the chuck to limit its movement. The chuck can be forced downward against its spring 28 by engagement of the projecting portion 19 of the driver head with the top surface thereof as shown in several of the figures, the spring 21 of course being superior to the spring 28. When so cooperating and the driver and the chuck descend together the point of the driver projects just far enough from the mouth of the chuck to set the nail below the surface of the work as the chuck rests on that surface. The operation is as follows:

The driver carries the nail through and out of the end of the chuck in the usual manner. The stroke of the driving head 4 is adjusted to advance the driver, without compressing the spring 21, a maximum distance that will just drive the nail home on the lowest working surface. Such surface 60 65 would be presented in nailing the first cover

on the end piece C, the cover D being absent. The two angled pieces B and C are then turned over and the cover D is applied as in Figure 6 which raises the working surface a distance equal to its thickness. 70 Upon this stroke of the head and driver the mouth of the chuck 10, nevertheless, strikes the surface of the work and halts the driver 14 so that it drives and sets the nail only as far as the driver projects beyond the 75 abutting end of the chuck. The rest of the normal travel of the driving head 4 is not effective upon the driver but is taken up by the compression of the spring 21. Of course the latter must be sufficiently strong to drive 80 the nail without yielding until the chuck abuts the work but not strong enough to cause the chuck to injure the work, such injury being further provided against by giving sufficient area to the lower end of the 85 chuck. Upon the return of the driver the chuck 10 follows it back under the influence of its own spring 28 the limited distance of its own travel in order to clear the next work piece to be placed on the table the 90 general idea being that when the driver and chuck come down together the chuck is carried into engagement with the work and 95 halts the driver at the proper point with a large enough bearing on the work to cause remaining movement of the driving head to be taken up by the driving spring 21.

The respective maximum and reduced strokes of the driver in another contingency are shown in a comparative way in Figures 100 2 and 3 both of which show the driving head 4 at its lower limit of movement as evidenced by its same position in the two figures while in the two cases the driver has completed its nailing stroke at two different elevations. Considering also Figure 1, in Figures 1 and 2 a relatively thin element E is being nailed to an element F while in Figure 3 a relatively thicker element G is being nailed to the same element F. Note 110 that in Figure 2 the spring 21 has not been compressed at all while in Figure 3 it is partially compressed.

The yielding nature of the driver of my invention is also useful in preventing injury 115 to the machine or the work piece in case a heavy nail strikes a strong obstruction or some impenetrable element is laid in the path of the driver.

I claim as my invention:

1. In a nailing machine, the combination with a support and a nail chuck independently mounted and having a reciprocatory movement thereon, of a driver extending 120 through the chuck and adapted to operate the latter against the work, a nailing head having a cycle of movement through a fixed path, and a spring interposed between the head and driver and through which the latter is operated. 125 130

2. In a nailing machine, the combination with a support of a nail chuck independently mounted and having a reciprocatory movement thereon toward and from the work, a spring acting between the chuck and the support for withdrawing the chuck from the work, a driver extending through the chuck and adapted to operate the latter against the work, a nailing head having a cycle of movement through a fixed path, and a spring interposed between the head and driver and through which the latter is operated.

3. In a nailing machine, the combination with a support having a guiding yoke thereon provided with a spring socket, of a nail chuck having a reciprocatory movement in the yoke toward and from the work, a spring in the socket reacting against the chuck to withdraw it from the work, a driver extending through the chuck and adapted to operate the latter against the work, a nailing head having a cycle of movement through a fixed path, and a spring interposed between the head and driver and through which the latter is operated.

4. In a nailing machine, the combination

with a support and a nail chuck independently mounted and having a reciprocatory movement thereon, of a driver extending through the chuck and provided with a shoulder adapted to engage and operate the latter against the work, a spring acting between the chuck and the support for returning the chuck, a nailing head having a cycle of movement through a fixed path, and a spring interposed between the head and the driver through which the latter is operated.

5. In a nailing machine, the combination with a frame and work holding means thereon, a nailing head movable toward and from the work, a support interposed between the work holding means and said nailing head, a plurality of chucks yieldably mounted for independent movement upon said support toward and from the work, nail driving members operable through the work engaging ends of the chucks adapted to move the latter into engagement with the work, and a spring interposed between each of said nail driving members and said head through which said nail driving members are operated.

HENRY W. MORGAN.
